UNITED STATES PATENT OFFICE.

WILLIAM C. EDWARDS, OF WINSTED, CONNECTICUT.

WASHING-MACHINE.

SPECIFICATION forming part of Letters Patent No. 378,243, dated February 21, 1888.

Application filed January 10, 1887. Serial No. 223,983. (No model.)

To all whom it may concern:

Be it known that I, WILLIAM C. EDWARDS, of Winsted, in the county of Litchfield and State of Connecticut, have invented a new and useful Improvement in Washing-Machines, of which the following is a specification, reference being had to the accompanying drawings, forming part thereof.

My invention relates to that class of washing-machines in which the clothes are agitated within a tub or other water-receptacle by means of vibratory bars or levers, and has for its object to improve such machines by providing novel means for alternately compressing and releasing the clothes, whereby they are thoroughly cleansed without being torn or otherwise injured.

To this end my invention consists in the construction and combination of parts herein-after fully described, and particularly pointed out in the claims.

Referring to the drawings, in which like letters designate like parts in the several figures, Figure 1 is a perspective view of a washing-machine constructed according to my invention. Fig. 2 is a transverse sectional view of the clothes receptacle and agitator. Fig. 3 is a similar view thereof in a different position. Fig. 4 is a perspective view of the clothes-receptacle and the hand-lever for operating the same, the operative position of said parts relatively to the tub or water-receptacle being indicated by dotted lines. Fig. 5 is a perspective view of the machine as arranged to be operated by power.

The tub or receptacle for the suds consists of the ends A, sides B, and cover C, said sides preferably converging to a point at the bottom, as shown, for the threefold purpose of economizing the material from which the tub is made, reducing the number of joints, thereby lessening liability to leakage, and to cause the water to constantly seek the lowest point, where it can be readily drawn off by removing plug c. The cover C is preferably provided with a centrally-located vertical extension, E, and with slots D, extending inwardly from one side, for purposes hereinafter set forth. The tub thus constructed will be supported by the legs a, united by braces b, as shown, or in any other suitable manner.

The clothes receptacle and agitator (shown in perspective in Fig. 4 and in transverse sec-

tion in Figs. 2 and 3) is constructed as follows: The ends are composed of two systems of compound levers, each consisting of the parallel bars K and transverse parallel bars L, arranged in the form of a parallelogram. The said bars are pivotally connected together at each point of intersection thereof by rods N, which extend from one parallelogram to the other, and with intermediate rods, O, form the four sides of the receptacle, said rods O being suitably secured to the bars forming the sides of the two parallelograms and serving to prevent the escape of the clothes from the receptacle. At one corner of the receptacle the bars O are omitted, as shown, to facilitate the insertion and removal of the clothes. The ends of the central rod, N, are extended beyond the ends of the receptacle to form journals I, by means of which the receptacle is suspended within the tub in the position indicated in Fig. 4, said journals I resting upon bearings secured to the inner side of the ends of the tub, which bearings are shown in dotted lines in said Fig. 4. The journals I thus serve as the fulcrum upon which the compound levers forming the ends of the receptacle operate.

The receptacle thus constructed can be made to assume either of the positions shown in Figs. 2 and 3 through the action of the compound levers, or can be still further compressed, if desired, until the opposite rods N or O contact with each other. By means of said levers, also, a vibrating movement imparted to either of the side rods will be communicated to the four sides of the receptacle simultaneously. It follows, therefore, that when the receptacle is supported, as previously described, within the tub, a vibratory movement imparted to one of the rods will cause the same to be compressed, first horizontally, as shown in Fig. 3, and then vertically.

In Figs. 1 and 4 I have shown as one means of imparting this movement to the receptacle a hand-lever composed of two parallel bars, G, having open slots W at one end and united at the opposite end by a hand-bar, F. The bars G are mounted upon a shaft, H, which journals in suitable bearings in the ends A of the tub, as shown in Fig. 1, the slotted ends of said bars extending within the tub and their outer portion lying within the slots D of the cover, previously described. The bearings for

said shaft H will preferably consist of open slots in the upper edge of the ends of the tub, near one side thereof, so that the operating-lever can be readily applied to and removed 5 from the tub, and will be retained in operative position by the cover C, which closes the mouth of said slots when placed on the tub.

The open slots W at the ends of bars G are designed to embrace one of the rods of the 10 clothes-receptacle, preferably the one designated by the letter M in Figs. 1 and 2, when the hand-lever is in operative position.

Instead of making the tub deep enough to 15 permit the vertical elongation of the receptacle beneath a flat cover, I prefer to provide the latter with a vertical extension, E, previously referred to, thereby affording ample space for the movements of the receptacle, with a considerable saving in the material from which 20 the tub is made.

The operation of the machine as thus far 25 described is as follows: The clothes (designated by the letter X in Fig. 4) being placed within the receptacle, and the tub being partially filled with suds, so that the clothes are 30 submerged therein, the operating-lever is placed in position with its end slots embracing rod M of the receptacle and its shaft H seated in its bearings in the ends of the tub, after 35 which the cover C is placed on the tub with its slots D embracing bars G of said lever. The operating-lever is then vibrated about its shaft by means of hand-bar F, causing the receptacle to be compressed first vertically and 40 then horizontally, agitating the clothes therein in such manner as to quickly and thoroughly remove all dirt and impurities therefrom; and the clothes being compressed against the central rod, N, by the rods composing the sides 45 of the receptacle and then released with every vibration of the operating-lever, there is no strain exerted upon them to injure them in any way.

It will be observed that the leverage exerted 45 by the levers K L upon the fulcrum consisting of the journals I adds materially to the ease with which the machine is operated, and this feature constitutes an important difference between the machine constructed according to 50 my invention and those heretofore devised, in which a collapsible and expansible agitator having four sides without the levers at the ends is employed. In these last-mentioned machines the agitator is secured either to the 55 bottom of the tub or to the cover thereof, and the entire weight of the clothes within the agitator comes upon the single main operating-lever, rendering the working of the machine an operation of much labor.

60 As it will sometimes be convenient and desirable to operate the machine by power instead of by hand, I have shown in Fig. 5 one arrangement of devices for such purpose, in which R designates a shaft driven by any suitable motor; S, one of the hangers for said shaft; T, a crank-disk upon said shaft; U, the crank-pin, and V a pitman operated by said disk

and crank-pin. The pitman at its lower end passes through a slot, P, in the cover of the machine, and is connected in any suitable manner to the rod N at the upper corner of the clothes-receptacle. Revolution of the shaft will, through the crank-disk and pitman, operate the receptacle in the same manner as previously described with reference to the 75 hand-lever.

It will be observed that the machine as above described is simple and inexpensive in structure and yet effective in operation.

So far as I am aware the clothes receptacle 80 and agitator above described is broadly new, and I therefore do not wish to limit myself to its use with the particular tub shown, as it is obvious that the latter could be modified in form and capacity without departing from this 85 feature of my invention. It is also obvious that other means for operating the receptacle could be substituted for those shown and described without affecting the novelty of the receptacle 90 itself.

I claim—

1. In a washing-machine, a collapsible clothes-receptacle consisting of parallel bars K and transverse parallel bars L at the ends, 95 said bars being pivotally connected at their intersecting points by rods N and intermediate rods, O, arranged and operating substantially as described.

2. In a washing-machine, the combination, 100 with a tub or suds-holder, of a clothes-receptacle consisting of the rods N, pivotally connecting at each end, the parallel bars K, with the transverse parallel bars L at the intersecting points of said bars, intermediate rods, O, and means for imparting a vibratory movement to one of said rods N, and through said rod to the receptacle, substantially as and for 105 the purpose set forth.

3. In a washing-machine, the combination, 110 with a tub or suds-holder, of a clothes-receptacle consisting of parallel bars K and transverse parallel bars L at the ends, rods N, pivotally connecting said bars, and intermediate rods, O, and having journals I at the ends, 115 and bearings located within the tub for supporting said journals, substantially as set forth.

4. The combination, with a tub or suds-holder, of the clothes-receptacle having the compound levers at the ends, rods N O, connecting said levers, and having the journals I 120 projecting beyond said ends and resting in suitable supports upon the inner side of the wall of the tub, and an operating-lever consisting of the bars G, shaft H, and hand-bar F, said shaft being journaled in the wall of 125 the tub, and said bars G having slotted inner ends embracing one of the rods of the clothes-receptacle, substantially as shown and described.

WILLIAM C. EDWARDS.
